UNITED STATES PATENT OFFICE

125,908

DESIGN FOR A COMBINED LUBRICATING OIL RACK AND WINDSHIELD CHAMOIS SERV- ICER

Dan R. Boisseau, San Antonio, Tex.

Application December 26, 1940, Serial No. 97,624

Term of patent 3½ years

To all whom it may concern:

Be it known that I, Dan R. Boisseau, a citizen of the United States, residing at San Antonio, in the county of Bexar and State of Texas, have invented a new, original, and ornamental Design for a Combined Lubricating Oil Rack and Windshield Chamois Servicer, of which the following is a specification, reference being had to the accompanying drawings, forming part thereof.

Figure 1 is a perspective view of a combined

lubricating oil rack and windshield chamois servicer, showing my new design.

Figure 2 is a view similar to Figure 1 but with the hoods of the end compartments in the head of the rack shown in open position.

I claim:

The ornamental design for a combined lubricating oil rack and windshield chamois servicer, as shown.

DAN R. BOISSEAU.
